UNITED STATES PATENT OFFICE.

FRANCIS M. BARTO, OF SANTA ANA, CALIFORNIA.

LUMBER-GUIDE MECHANISM.

No. 893,895.

Specification of Letters Patent.

Patented July 21, 1908.

Application filed November 26, 1907. Serial No. 403,848.

To all whom it may concern:

Be it known that I, FRANCIS M. BARTO, a citizen of the United States, residing at Santa Ana, in the county of Orange and State of California, have invented certain new and useful Improvements in Lumber - Guide Mechanism; and I do hereby declare the following to be a full, clear, and exact description of the invention, such as will enable others skilled in the art to which it appertains to make and use the same.

This invention relates to guide mechanism used in piling lumber; and it consists in the novel construction and combination of the parts hereinafter fully described and claimed.

In the drawings, Figure 1 is a side view of the guide mechanism. Fig. 2 is a front view of the same.

A is a frame provided with vertical side-bars B having outwardly curved lower end portions b. C are horizontal arms which project rearwardly from the upper parts of the side-bars B at a short distance below their top portions. These arms C are provided 25 with sharp pointed hooks c at their rear ends which project downward, and D are brace-plates secured in the angles between the arms and side-bars and securing them in position. E are crossbars arranged between 30 the side-bars and between the arms, and which complete the said frame.

F is a serrated roller mounted to revolve between the upper end portions of the side-bars B, and f is the shaft which supports the 35 said roller. This roller is preferably hollow, and it has a ratchet toothed wheel G secured

to one end of it. A gravity pawl g is pivoted to one of the side-bars B by a pin h, and it engages with the teeth of the wheel G so that the said roller can be revolved freely in the 40 direction of the arrow in Fig. 1, but not in the reverse direction.

The frame A is hooked onto the top of a pile of lumber, or any other stationary support, and the boards to be placed on top of 45 the pile are slid upon the serrated roller which permits them to be slid upward, but hinders them from sliding downward.

This device is used to facilitate the piling of lumber, and its use is found to be very 50 advantageous.

What I claim is:

In a lumber guide, the combination, with a frame formed of two side-bars and a series of crossbars extending between the said side-bars, of a roller journaled in the upper end portions of the said side-bars and arranged in the same plane as the said crossbars, laterally projecting arms secured to the said side-bars under the axis of the said roller and provided with hooks at their ends, brace-plates secured in the angles between the said arms and side-bars, and ratchet mechanism which permits the said roller to be revolved in one direction only.

In testimony whereof I have affixed my signature in the presence of two witnesses.

FRANCIS M. BARTO.
